UNITED STATES PATENT OFFICE.

EMIL BENTE AND PAUL STUHLMANN, OF BARMEN, GERMANY, ASSIGNEES TO MAX HENKELS, OF NEW YORK, N. Y.

LACE PRODUCED ON THE SINGLE-THREAD LACE-BRAIDING MACHINE.

Application filed December 27, 1922. Serial No. 609,272.

To all whom it may concern:

Be it known that we, EMIL BENTE and PAUL STUHLMANN, citizens of the German Empire, residing at Barmen, Germany, have invented certain new and useful Improvements in Lace Produced on the Single-Thread Lace-Braiding Machine, of which the following is a specification.

Our invention relates to the production of lace, and more particularly to lace made on the single-thread braiding machine, and of which the ground-work consists wholly or in part of triangular meshes.

One object of our invention is to produce lace of the stated characteristics in an exceptionally economic and rapid manner by reason of the relatively small number and the relatively short lengths of the threads required. Another object of this invention is to produce a lace of the character set forth which will resist to an eminent degree distorting influences, to which the lace may be subjected in handling, by reason of the threads being firmly interlocked at the crossing points of the network.

With these and other objects in view our invention comprises the particular steps hereinafter fully described and set forth in the appended claims.

To the ground of the lace any desired patterns of the type producible on the single-thread lace-braiding machine, for example, tufts, spiders, leaflets or the like, may be provided, thus rendering the new lace particularly valuable.

Our lace and the process of making the same are fully set forth in the following description, reference being made to the annexed drawing, which illustrates, by way of example, two embodiments of the lace, and in which show—

Fig. 1 a part of a lace provided with a socalled tuft on a greatly enlarged scale,

Fig. 2 the ways of the bobbin-carriers in producing the ground of the lace shown in Fig. 1 on the single-thread lace-braiding machine,

Fig. 3 a part of an alternative lace, also on an enlarged scale.

Referring now specially to Fig. 1, the groundwork of the lace is composed of an unlimited number of warp-like longitudinal strips *a*, *b*, *c*, *d*, *e*, each consisting of two entwisted threads, 2, 3, 5, 6, 8, 9, 11, 12 and 14, 15 respectively, and of a compara-

tively wide-meshed net consisting of diagonally arranged threads 1, 4, 7, 10, 13, 16 crossing one another at certain intervals. Said diagonal threads serve like the weft of a web to connect the longitudinal strips *a*, *b*, *c*, *d*, *e* and to lock them in their correct distances. For this purpose the diagonal threads 1, 4, 7, 10, 13, and 16 are at their

crossing points braidedly connected to the said longitudinal strips by all crossing points *a*, *b*, *c*, *d*, *e* and to lock them in their correct distances. For this purpose the diagonal threads 1, 4, 7, 10, 13, and 16 are at their

crossing points braidedly connected to the said longitudinal strips by all crossing points *a*, *b*, *c*, *d*, *e* and to lock them in their correct distances. For this purpose the diagonal threads 1, 4, 7, 10, 13, and 16 are at their

crossing points braidedly connected to the said longitudinal strips by all crossing points *a*, *b*, *c*, *d*, *e* and to lock them in their correct distances. For this purpose the diagonal threads 1, 4, 7, 10, 13, and 16 are at their

crossing points braidedly connected to the said longitudinal strips by all crossing points *a*, *b*, *c*, *d*, *e* and to lock them in their correct distances. For this purpose the diagonal threads 1, 4, 7, 10, 13, and 16 are at their

crossing points braidedly connected to the said longitudinal strips by all crossing points *a*, *b*, *c*, *d*, *e* and to lock them in their correct distances. For this purpose the diagonal threads 1, 4, 7, 10, 13, and 16 are at their

crossing points braidedly connected to the said longitudinal strips by all crossing points *a*, *b*, *c*, *d*, *e* and to lock them in their correct distances. For this purpose the diagonal threads 1, 4, 7, 10, 13, and 16 are at their

crossing points braidedly connected to the said longitudinal strips by all crossing points *a*, *b*, *c*, *d*, *e* and to lock them in their correct distances. For this purpose the diagonal threads 1, 4, 7, 10, 13, and 16 are at their

crossing points braidedly connected to the said longitudinal strips by all crossing points *a*, *b*, *c*, *d*, *e* and to lock them in their correct distances. For this purpose the diagonal threads 1, 4, 7, 10, 13, and 16 are at their

crossing points braidedly connected to the said longitudinal strips by all crossing points *a*, *b*, *c*, *d*, *e* and to lock them in their correct distances. For this purpose the diagonal threads 1, 4, 7, 10, 13, and 16 are at their

and from in the transversal direction of the tuft B between said four heavily tensioned threads. Both groups of thread forming the tuft being thereby interlaced in a web-like manner, the lightly tensioned threads at the same time crossing one another in the space between each two adjacent threads 5, 8, 9 and 12. Of course, instead of a tuft, a leaflet, that is some sort of tuft 10 with pointed ends, or a spider or a similar pattern may also be applied to the lace-ground.

Fig. 2 illustrates the formation of the new ground-work on the single-thread lace-braiding machine. The plates of the machine, shown in the left-hand part of that figure are occupied by the bobbin-carriers 1^a, 2^a, 3^a, 4^a, 5^a, 6^a, 7^a, 8^a, 9^a, 10^a, 11^a, 12^a, 13^a, 14^a, 15^a and 16^a, one part of said carriers having bobbins with heavily tensioned threads on it, another part carrying bobbins with lightly tensioned threads. The former are marked by black points, the latter by small circles. The ways of the 25 bobbin-carriers are shown in the right-hand part of Fig. 2 by means of fine and bold strokes of the pen. In this part of the figure the spaces between the horizontal auxiliary lines correspond to the 30 plates, whereas the spaces between the vertical auxiliary lines correspond to one half revolution of the drivers. Those fine and bold strokes of the pen which run diagonally mean either movements of the respective bobbin-carriers on one and the same plate, i. e. twisting of threads, or transfers of the carriers from one plate to another, i. e. interchange of bobbins between adjacent plates. Finally, the strokes of the 35 pen running co-directionally with the horizontal auxiliary lines mean arrest of the respective bobbin-carriers. As is evident from an inspection of Fig. 2 only a comparatively few stand-stills of the bobbin-carriers occur, therefore the work is rapid and economical.

In Fig. 3 an alternative form of our new lace-ground is illustrated. In this example, the diagonal threads 17, 20, 21, 24, 25, 28, 29 and 32 forming the wide-meshed net 50 for connecting the longitudinal strips f, g, h, i are not only crossed within said strips, but are also (at B, B) crossed in the mid-

dle of the spaces between each pair of adjacent strips. By this means a lace may be produced which, although containing merely 55 one and a half times as many threads as the lace shown in Fig. 1; is twice as broad as the latter. Consequently, when making the lace ground according to Fig. 3, the quantity of threads necessary for producing a 60 lace of great width is still more reduced than with the ground-work of Fig. 1. The required braiding machine may also be a smaller one. Of course, to the lace-ground shown in Fig. 3 also tuft, leaflets, spiders 65 or other patterns producible on the single-thread lace-braiding machine may be applied.

We wish to state that our invention is not restricted to the examples shown and 70 described. On the contrary many other embodiments may suggest themselves to those skilled in the art without departing from the spirit of our invention as pointed out in the following claims.

75

Claims:

1. A braided lace of the character set forth, having triangular meshes, which is composed of spaced warp pillars, each consisting of but two threads, twisted together, 80 and a net work of rhombic meshes, consisting of single threads running diagonally across the warp pillars, said diagonal threads crossing each other within the warp pillars and being braidedly interlocked with 85 the latter at the crossing points.

2. A braided lace having triangular and rhombic meshes which comprises spaced warp pillars, each pillar consisting of but two threads, twisted together, and a net 90 work of rhombic meshes, consisting of single threads running diagonally across the warp pillars, said diagonal threads crossing each other within the warp pillars and also in the spaces between the latter and 95 braidedly interlocked with the warp threads at the respective crossing points.

In testimony whereof we affix our signatures in presence of two witnesses.
